UNITED STATES PATENT OFFICE

JESSE A. B. SMITH, OF STAMFORD, CONNECTICUT, ASSIGNOR TO UNDERWOOD ELLIOTT
FISHER COMPANY, OF NEW YORK, N. Y., A CORPORATION OF DELAWARE

TYPEWRITER CARRYING CASE

Application filed September 15, 1930. Serial No. 481,874.

This invention relates to portable typewriting machines, in which it is usual to fasten the machine to a baseboard, to which is detachably connected a cover, having a handle for transportation.

It is desired to make provision for keeping the typewriter covered up while it rests out of use upon a library desk or table. This invention overcomes the difficulty that a closed portable typewriter is not of such design or attractiveness as to make it suitable for library use, or to comport with the usual furnishings of the home libraries.

To overcome this difficult, it is a feature of this invention to provide means for interchangeably mounting the typewriter either in a carrying case or in a case which is specially fitted to stand upon a library desk or table. To this end, the baseboard of the typewriter is made to fit into the transportation case or the library case, interchangeably, so that the machine may either be carried about or kept indefinitely upon the library table, forming an attractive feature of the library.

The library case is made and finished to resemble a set of volumes, forming an attractive device to stand upon a desk.

The machine stands upon its back when stored in the library case, and the baseboard closes the same, excluding dust and dampness. The baseboard may be locked so as to prevent unauthorized persons from gaining access to the machine.

The openings in the two cases are similar, and are provided with similar catches and other fittings to secure interchangeability.

Preferably the library case is provided with a detachable stationery rack or set, including a tier of pockets mounted in the back of the library box, with means for preventing the stationery from dropping out of the pocket when the box is inverted.

It will be understood that the carrying case can be of the usual inexpensive type, suitable to withstand harsh usage in transportation.

while the library case may be of more expensive design, and fitted to constitute a piece of furniture and make a substantial and ornamental contribution to the appearance of the library in which it is used.

Other features and advantages will herein-after appear.

In the accompanying drawing, Figure 1 is a perspective view, showing the baseboard with the typewriting machine contained in the traveling case.

Figure 2 is a perspective view, showing in dotted lines the position of the baseboard when the machine is fastened within the cabinet.

Figure 3 is a sectional elevation, showing the machine packed away in the cabinet.

Figure 4 is a perspective view, showing the machine withdrawn from the cabinet, and also showing the stationery rack separated from the cabinet.

The typewriting machine 10 is rigidly secured in the usual manner to a baseboard 11, upon which the machine stands when in use, as seen in the lower part of Figure 4. For transportation purposes, the baseboard may be fastened in the usual cover 12 having a handle 13. The cover is provided with a key-lock 14, and the baseboard has a headed locking stem 15 to co-operate therewith.

The baseboard 11 may also be used whenever it is desired for the purpose of storing the machine in the desk-cabinet 16, without removing the machine from the board. At Figure 3 the cabinet is seen standing upon a desk 17, and the board, carrying the machine, is confined at its lower edge by hooks 18 fastened in the bottom 19 of the cabinet; while at its upper edge its locking stem 15 is confined in a lock 20 that is provided upon the top of the cabinet. The board 11 seals the interior of the cabinet against dust and dampness.

In the upper and lower corners of the cabinet may be provided reinforcements 21, which

serve as stops against which the baseboard is set, as at Figure 3.

The desk-cabinet has the shape of a set of standing volumes 22, suitable for use in the library.

This set may furnish a broad base, to minimize the liability of upsetting, and thus space is furnished within the box for a stationery rack 23 having partitions 24, 25, to divide the rack up into a number of compartments for work-sheets 26 of various sizes.

The rack includes a back wall 27, which is detachably held against wall 16 of the box by means of a bolt 28 catching over the top

edge of said wall. At its bottom the rack is confined between the bottom stops 21 and the rear wall 16 of the cabinet. The partitions may be provided with clips 29, catching over the tops thereof and formed with

bow-spring portions 30, clipping the paper back against the partitions or walls, to retain the sheets when the cabinet is turned upside down.

The front wall 31 of the partition is provided with cushions or rests 32, against which sets the platen 33 of the typewriter, preventing accidental movement thereof.

The side wall 34 of the rack may be provided with a bracket 35 to hold fountain pens 36; and the front wall 31 may have a clip 37 for an eraser 38. When it is desired to remove the tray, a thumb-screw 39 may be loosened, and the bolt 28 may be slipped up, whereupon the rack may be tilted upwardly and withdrawn from the cabinet.

Variations may be resorted to within the scope of the invention, and portions of the improvements may be used without others.

Having thus described my invention, I claim:

1. A typewriter cabinet for portable typewriters permanently closed on its four sides and one end, a typewriter baseboard with

the typewriter attached thereto serving to close the other end, attaching means releasable to allow the baseboard and typewriter to be folded down into typewriter operative position, bottom and top reinforcing strips serving as stops to hold the typewriter baseboard from inward movement, a rack for stationery with its bottom held in position in

said cabinet by said bottom strips, said rack terminating at its upper portion below the top of the casing whereby when the typewriter and baseboard have been folded down to typing position the rack may be lifted clear of the stops at the bottom of the cabinet and removed therefrom and a latch above the

rack for releasably holding its top portion against the closed side of the casing.

2. A typewriter cabinet comprising a casing permanently closed on all its sides except one, a typewriter baseboard fitting the open side of the casing and detachably held in po-

sition and when removed leaving an opening constituting the only means of access to the interior of the casing, a rack for stationery with means to detachably hold the rack at its bottom against a closed side of the casing, the rack being less in height than the casing whereby when the typewriter baseboard carrying the machine is turned to horizontal position the rack may be lifted to release it from said holding means and moved through the opening that is normally closed by the typewriter baseboard.
